UNITED STATES PATENT OFFICE.

GEORGE W. HALL, OF JACKSON, MISSISSIPPI.

COTTON-GIN RIB.

Application filed November 10, 1927. Serial No. 232,384.

This invention relates to improvements in cotton gin and linter breasts.

An object of this invention is to provide an improved cotton gin rib which may be held in position by a supporting element located at the bottom of the breast and arranged for an adjustability through the medium of a sliding clamp device at the top of the breast thereby greatly facilitating and 10 simplifying the assembling of the gin breast or grate fall at the factory or in the gin house. The rib according to this invention may be used in place of the ordinary type of rib held in position by a plurality of wood screws 15 adapted to fasten the rib at the top and bottom of the wooden rails.

Another object of this invention is to provide an improved gin rib constructed in such a manner as to insure positively proper spacing and setting of the ribs in order that the 20 saws commonly used in cotton gins can be positioned accurately in the relationship to the ribs.

The improved gin rib according to this invention is constructed to avoid the necessity of shimming at the top and bottom of the rib in order to make it conform to positive alignment and at the same time to insure a uniform width for all the rib elements and 25 the maintenance of the proper center for the saws thereby making the breast interchangeable as may be desired.

Other objects of this invention are to provide an improved screwless gin and linter breast which will eliminate the necessity of skilled labor for building up or assembling its 30 different elements, and to avoid the use of all screws or other similar fastening devices in the gin rib, also to eliminate the need of training each rib on the rib rails so that the saws will not strike, as is the case with the old and common structure now in use. This invention is adaptable on any make of gin or linter owing to the fact that the curve or shape of 35 the rib may be designed to conform with the standard rib of any particular apparatus. The parts may be easily replaced in case of broken or worn parts, and are accurately milled by machinery therefore making the 40 sections interchangeable.

Other objects of this invention will appear from the following detailed description of the device and as disclosed in the single sheet of drawings which is herewith made a part 45 of this application.

In the drawings—

Figure 1 illustrates an end elevational view of the cotton gin breast disclosing the gin rib, huller rib, and top and bottom rib rails in assembled and operative relation with the 50 saw element of a cotton gin.

Figure 2 represents a front elevational view of a portion of cotton gin breast disclosing the top and bottom rib rails in operative relation with the gin ribs and huller ribs, 55 also disclosing the adjustable means for holding the gin ribs in position at the top of the breast.

Figure 3 illustrates a perspective view of the adjustment bar adapted to hold the gin 70 ribs in position.

Figure 4 represents a perspective view of the metal base supporting elements for the bottom of the ribs.

Figure 5 represents a sectional view of Figure 2 taken along line 5—5.

Figure 6 illustrates a front elevational view of the adjustment bar for holding the huller ribs in position.

Numerical 1 designates the top rib rail of the cotton gin breast made preferably of wood and adapted to be securely fastened thereto by means of screw elements 2 or otherwise is a base plate 3 made of any suitable material preferably metal, while arranged in slidable contact with the base plate 3 is an adjustable bar 4 made of any suitable material such as metal and adapted to be securely fastened by means of screw elements 5 to a section of the roll box 6. A gin rib 7 is adapted to be made 80 of any suitable material and constructed so as to conform with the requirements of the gin apparatus upon which it is to be used. The upper end of the gin rib 7 is adapted to be held in operative relation by means of the 85 adjustably arranged bar 4 and the base plate 3, while the bottom end of the gin rib 7 is constructed so as to be maintained in operative relation by means of a base plate 8 made of any suitable material and adapted to be securely fastened to a bottom rail element 9 by means of screw or other fastening elements 10, the bottom rib rail being preferably 90 made of wood while the base plate 8 may be constructed preferably of metal.

One of the prime objects of this invention is to provide an improved gin rib which may be securely held in position without the use of fastening elements at the top and bottom now commonly utilized for securely connect- 100 105 110

ing the top and bottom ends of the ribs to the wooden rib rails. In order to accomplish the desired results it is preferred in this invention to bevel the top and bottom of the gin rib 7 as at 11 and 12 in such a manner that the beveled ends may cooperate with the adjustable plate 4 and the base plate 8 in such a manner that they will be brought into secure and interlocked relation thereby avoiding the use of any fastening element between the gin rib and the top and bottom rib rails. The top and bottom beveled portions 11 and 12 are arranged so that they may be easily adjusted for the proper spacing and alignment of the ribs in order that the gin saw elements 13 may be properly positioned. In order to assure a close fitting connection between the back of the rib 7 at the top and bottom it is preferred that the portions which are adjacent to the upper and bottom base plates 3 and 8 be carefully ground so as to set squarely therewith as at 14 and 15 thereby avoiding the necessity of shimming of the top and bottom of the rib.

In cooperation with the cotton gin breast saw 13 and the gin rib 7 of the cotton gin breast is arranged a huller rib 16 made of any suitable material such as metal and adapted to have beveled portions at its upper and lower ends as at 17 and 18 so formed as to be held in interlocked relation at its upper end by means of an adjustably arranged plate 19 properly connected by means of element 20 to a base plate 21 and rail 22. The base plate 21 is made of any suitable material such as metal and adapted to be securely fastened to the rail element 22 by means of screws 23 or otherwise, the adjustable bar or plate 19 being so constructed that it will release or hold the huller rib in position as may be desired.

The lower bevel end 18 of the huller rib 16 is brought into interlocked relation with a base plate 24 adapted to be securely held in position on a lower huller rib rail 25 by means of screws 26 or otherwise. It is apparent therefore that the huller rib 16 may be held securely in position without the use of fastening elements at its upper or lower ends and efficient means have been provided for the required adjustability. A suitable brace 27 is provided for holding the top and bottom rib rails in position and may be made to conform with the requirements of the gin on which it is to be used.

The bar 4 is arranged for adjustability in order to allow the gin ribs 7 to be placed in position or removed as may be desired and is preferably provided in each end with slotted portions 28 and 29 adapted to receive in adjustable relation therewith a bolt 30 and a wing nut 31. When the gin ribs 7 are desired to be removed, the wing nut 31 is loosened and the bar 4 raised making it a simple matter to remove the ribs.

In operation this invention provides a very efficient gin and linter breast particularly in the matter of the gin ribs and huller ribs which are held in interlocked relation with the top and lower rib rails without the use of screws or fastening elements in the gin rib themselves. It is now the common practice to use anywhere from three to four screws in each rib and inasmuch as there are 81 ribs more or less to each gin breast and 101 ribs to each linter breast it can be readily perceived that a great saving in time, labor and expense has been brought about through this invention. It is also a very simple matter with the gin ribs constructed and arranged according with this invention to assemble or build up the gin or linter breast inasmuch as the ribs are so designed as to maintain the same centers between each rib in order that the saws when trained to the same gage on cylinders and properly set in center of space between the ribs will run without striking ribs and will be interchangeable. Furthermore the assembling may be easily done by unskilled labor as the ribs according to this invention are merely set in place on the rib rails and are held there securely by a clamp bar whereas the old device required that each rib be fastened to the top and bottom rib rails. The gin and linter breast according to this invention may be used on any make of gin or linter by merely constructing the curve or shape of the rib to conform with the standard rib of the particular gin or linter under consideration. Furthermore broken or worn ribs may be easily replaced with new ones without damaging or inconvenience in dismantling.

It is to be understood that alterations and substitutions in the above disclosure may be made within the scope of the appending claims without affecting the merits of the invention.

What I claim is:

1. In a cotton gin breast having a plurality of rib portions, an upper rib rail and base member attached thereto, an element slidably arranged in relationship to the base member for adjustably holding the upper ends of the rib portions in position, a lower rib rail and a base section attached thereto for adjustably holding the lower ends of the ribs in position.

2. In a cotton gin breast having a plurality of rib portions, an upper rib rail and base member attached thereto, an element slidably arranged in relationship to the base member for adjustably holding the upper ends of the rib portions in position, a lower rib rail and a base section attached thereto for adjustably holding the lower ends of the ribs in position, braces for holding the upper and lower rib rails in position.

3. In a cotton gin breast having a plurality of rib portions, an upper rib rail and base

- member attached thereto, an element slidably arranged in relationship to the base member for adjustably holding the upper ends of the rib portions in position, a lower rib rail and a base section attached thereto for adjustably holding the lower ends of the ribs in position, braces for holding the upper and lower rib rails in position, a roll box section attached to the adjustable element.
5. In a cotton gin breast having a plurality of rib portions, an upper rib rail and base member attached thereto, an element slidably arranged in relationship to the base member for adjustably holding the upper ends of the rib portions in position, a lower rib rail and a base section attached thereto for adjustably holding the lower ends of the ribs in position, braces for holding the upper and lower rib rails in position, a roll box section attached to the adjustable element, a plurality of auxiliary ribs spaced from the rib portions.
10. 4. In a cotton gin breast having a plurality of rib portions, an upper rib rail and base member attached thereto, an element slidably arranged in relationship to the base member for adjustably holding the upper ends of the rib portions in position, a lower rib rail and a base section attached thereto for adjustably holding the lower ends of the ribs in position, braces for holding the upper and lower rib rails in position, a roll box section attached to the adjustable element, a plurality of auxiliary ribs spaced from the rib portions, an adjustable element for holding the auxiliary ribs in position.
15. 5. In a cotton gin breast having a plurality of rib portions, an upper rib rail and base member attached thereto, an element slidably arranged in relationship to the base member for adjustably holding the upper ends of the rib portions in position, a lower rib rail and a base section attached thereto for adjustably holding the lower ends of the ribs in position, braces for holding the upper and lower rib rails in position, a roll box section attached to the adjustable element, a plurality of auxiliary ribs spaced from the rib portions, an adjustable element for holding the auxiliary ribs in position.

In testimony whereof I affix my signature.

GEO. W. HALL.
